UNITED STATES PATENT OFFICE.

THOMAS F. MCCULLOUGH, OF MEMPHIS, TENNESSEE.

DESIGN FOR A GARMENT-SUPPORTER JAW.

SPECIFICATION forming part of Design No. 35,356, dated December 3, 1901.

Application filed October 30, 1901. Serial No. 80,562. Term of patent 3½ years.

To all whom it may concern:

Be it known that I, THOMAS F. MCCULLOUGH, a citizen of the United States, and a resident of Memphis, in the county of Shelby and State of Tennessee, have invented and produced a new and original Design for a Garment-Supporter Jaw, of which the following is a specification, reference being had to the accompanying drawings, forming part thereof, in which—

Figure 1 is a side view, slightly in perspective, showing a garment-supporter jaw embodying my design; and Fig. 2 is a section on the line 2 2 of Fig. 1.

The design presents the body part *a* with the jaw part *b* below it. These parts are each formed of two sections of material lying side by side. The body *a* terminates at its upper end in an eye *c*, while the lower end of the jaw *b* presents a reduced extension *d*. The

side edges of the body are serrated, as at *a'*, and the jaw *b* has a concave serrated edge *b'*, the serrations of which run into the extension *d*.

The leading feature of the design is the 25 concave serrated edge *b'*, running into the serrated edge of the extension *d*.

Having described my invention, what I claim as new, and desire to secure by Letters Patent, is—

The design for a garment-supporter jaw, as herein shown and described.

In testimony whereof I have signed my name to this specification in the presence of two subscribing witnesses.

THOMAS F. MCCULLOUGH.
